NONREEMPTYING BOTTLE

Lester L. Lewis, Cabot, Pa.

Application August 19, 1937, Serial No. 159,967

7 Claims. (Cl. 215—18)

This invention relates to improvements in containers of the type designed to prevent misrepresentation regarding the contents and as such is in the form of a non-refillable receptacle.

In the art to which the present invention relates efforts have been popularly made to prevent the refilling of receptacles, such as bottles, in order to avoid the possibility of either the offering of a spurious substitute or the illegal marketing 10 of a refilled bottle or other receptacle. Quite extensive efforts have, accordingly, been exerted in the direction of preventing the refilling of bottles and like receptacles, and containers and such receptacles have come to be commonly known as non-refillable bottles even though it is well known that it is practically impossible to actually prevent refilling because of the advance that has been made in the welding of glass by which it is possible to either remove the bottom 20 of a glass receptacle and re-weld it in a manner not observable, or it is possible to drill through an appropriate part of the wall of the receptacle and after filling weld the opening thus formed in a not readily detectable manner.

It is, therefore, not sufficient to provide means to prevent liquid being introduced into a bottle or other receptacle through the opening from which liquid is intended to be discharged. Accordingly, the present invention provides the 30 novel combination of means for preventing the refilling of a receptacle through the port or opening through which its contents is intended to be regularly discharged with means for preventing discharge of the contents of the same receptacle, if the receptacle be refilled by any means after it shall have been completely discharged 35 through the regular discharge opening.

In other words, the novel idea of the present invention is directed to preventing discharge of the 40 contents of a receptacle after the receptacle has once been emptied rather than, or supplemental to, the effort to prevent refilling, so that the present invention may be tersely described as a combination of parts providing a non-re- 45 emptyable receptacle.

With this and more detailed objects in view as will in part hereinafter become apparent and in part be stated, the invention includes means, in combination with a receptacle, to control the 50 once emptying of the contents of a filled receptacle, and thereafter prevent a second emptying thereof unless accompanied by such breakage as to plainly indicate the fact of the second filling.

The invention further comprises a control of 55 the measuring type for governing the discharge

of the contents of a receptacle and means co-operating therewith for precluding further discharge after an amount has been discharged substantially equal to the capacity of the receptacle.

The invention also includes in greater detail in 5 such an arrangement means for preventing repetition of the measuring operation or restoration thereof to a condition enabling such repetition.

The invention also comprises certain other 10 novel constructions, combinations, and arrangements of parts as subsequently specified and claimed.

In the drawings:

Figure 1 is a fragmentary sectional elevation of a structure embodying the features of the present 15 invention;

Figure 2 is a complete central section taken on substantially the same plane as the plane of the section of Figure 1;

Figure 3 is an exploded perspective of the 20 valve operating member forming part of the said invention;

Figures 4, 5, 6, and 7 are horizontal sections taken substantially on the planes indicated by the lines 4—4, 5—5, 6—6, and 7—7 of Figure 2; 25

Figure 8 is a fragmentary sectional elevation of a slightly modified form of the invention; and

Figure 9 is a fragmentary central vertical section through another modification.

In the drawings the invention is illustrated 30 as applied to a glass bottle 10, of standard shape, provided with a neck 11. The closure or "cork" for the bottle comprises a cylindrical stopper 12 provided with an annular groove 13 deep enough to receive and enclose a split washer 14 35 of springy material. The inner surface of the bottle neck 11 is also provided with a groove 15 adapted to register with the groove 13 in the stopper 12. In applying the stopper to the bottle neck the split washer 14 is first sprung into the 40 groove 13 and forced below the outer surface of the stopper. Next, the stopper and its split ring, is inserted in the mouth of the bottle neck and moved therewith, until the split washer springs into the groove 15 while a substantial part of the 45 washer remains in the groove 13 to lock the stopper permanently in sealing position.

The stopper is provided with an axial bore 16 to receive a shaft 17 having its upper end reduced to form a square sectioned lug 18 to which 50 is cemented a knurled knob 19. At its lower end the shaft 17 is reduced to form a square sectioned lug 20 which is slidably mounted in a correspondingly sectioned axial bore 21 formed in the upper end of the shaft extension 22.

The stopper is provided with a discharge aperture 23; and is also provided with a cylindrical recess 24, the bottom of which forms a stop for one end of a compression spring 25 coiled around the shaft 17. The other end of the spring 25 presses against a valve disk 26' fixed to the shaft 17 and provided with a series of apertures 26, 27, 28, and 29, equidistantly spaced from the axis of said shaft and equiangularly spaced around the end axes.

The lower face of valve disk 26' has an annular row of ratchet teeth 30 formed thereon for yielding engagement with a similar row of teeth 31 formed on the upper face of a cylindrical measuring block 32, axially bored to receive slidably and rotatably the shaft or stem 17. The upper and lower parts of the block 32 are formed as fixed disks 33 and 34, respectively, each provided with a series of axially aligned apertures. The apertures 35, 36, 37, and 38 are adapted to register with the apertures 26, 27, 28, and 29, when the valve disk 26' is in liquid dispensing position. As shown in Figure 4 the valve disk 26' is located in position to close the apertures 35, 36, 37, and 38.

The apertures 39, 40, 41, and 42 formed in the fixed disk 34 are likewise adapted to register with the apertures 43, 44, 45, and 46, respectively, formed in a valve disk 47 fixed to the shaft extension 22. As shown in Figures 3, 4, and 5, the apertures in the upper and lower valve disks 26' and 47 are angularly displaced; so that when the disk 26' is in position to close the apertures in the fixed disk 33, the lower valve disk 47 has its apertures registering with those in the fixed disk 34, and vice versa.

The fixed disks 33 and 34 are connected by the hollow cylindrical member 32, which is cut away at opposite sides to provide additional volume for liquid to be measured between the opposite faces of the fixed disks 33 and 34. It is obvious that by cutting away parts of the cylindrical wall connecting the said fixed disks, the volume will be correspondingly increased by the amount cut away.

The valve disk 47 is seated on a shoulder 49 formed by an enlarged screw threaded lower part 50 of the shaft extension 22. A nut 51 is mounted on the part 50 and is cut away to form radially projecting lugs 52, 53, 54, and 55 projecting into slots 56, 57, 58, and 59, respectively, formed in a cylindrical cage 60, which is seated and fixed at its upper end in an annular recess 61 formed in the fixed valve disk 34.

In the modification illustrated in Figure 8, the valve disk 26' of Figures 1 and 2 is replaced by a valve disk 62 having its lower face smooth to seat and rotate with the shaft 63 on the upper plane end of a measuring block 64, which in every other respect is identical with measuring block 32.

In this form, the valve disk 62 has an annular row of ratchet teeth 65 formed on its upper face and adapted to be engaged by a leaf spring 66 suitably secured at one end to the lower face of the fixed stopper 67. The shaft 63 is made in one piece to replace the shaft 17 and its extension 22, since the modified ratchet mechanism does not require the shaft to reciprocate axially in the measuring block.

The modification shown in Figure 9 is designed to permit discharge of the contents of the bottle axially of the stopper 68 which is mounted to rotate in the mouth of the bottle neck 11. In this form of the invention, all the elements, with

the exception of shaft 59, are structurally the same as the elements shown in Figures 1 and 2, and are similarly secured to each other in the bottle neck. Accordingly, such of these similar elements as are shown in Figure 9 are identified by the same reference numerals primed, and are not further described.

The stopper 68 is provided with an axial bore 70, square in cross-section and adapted to receive slidably a similarly cross-sectioned lug 71 projecting axially from the upper end of the shaft 69. It is to be understood that the lower end of shaft 59 is slidably connected to an extension as shown in Figure 2 of the drawings.

The valve disk 26'' is fixed to the shaft 69, and serves as an abutment for one end of the compression spring 25', coiled around the upper end of the shaft 69. The other end of the spring 25' seats on the bottom of an annular recess 71 formed in the stopper 69 coaxial with the axis 20 of the bore 70.

The discharge outlet 72 is formed in the stopper 68 so as to emerge at the outer end of the axis thereof. In this form, part of the stopper projects outwardly from the bottle neck and forms a hand grip to facilitate turning of the stopper and the elements fixed thereto.

It is believed the operation of the various forms of this invention will be obvious to persons skilled in the art without further description. However, it should be understood that if an operator chooses, he can, at any time the apertures in the valve disk 26' and the fixed disk 33 are in registration, pour liquid through the discharge aperture 23 and through these registering apertures into the measuring block 32. Of course, when the upper series of apertures are in this position, the apertures in the valve disk 47 are in closed position. Therefore, when the measuring block 32 has been filled as indicated, the contents thereof may be introduced into the bottle itself by giving the knob 19 a sufficient turning movement to close the apertures in the upper fixed disk 33 and open those in the lower fixed disk 34. Such an introduction of liquid cannot be of any material value to the operator, however, since he has lost just that much in the longitudinal outward movement of the nut 51, which is the controlling factor in the emptying of the receptacle.

When the nut 51 has reached its limit of movement toward the valve disk 47, there is nothing to allow the escape of any liquid which might remain in the bottle. Accordingly, the threaded part of the extension 22 is made slightly longer than the available number of dispensing movements in the ratchet mechanism in the upper end of the closure, so as to provide for a complete emptying of the receptacle within reasonable limits, and to insure against accidental movement of the operating knob 19 having the effect of rendering some of the original contents inaccessible.

After the bottle has once been completely emptied and the nut 51 has reached its limit of travel against the lower valve disk, any filling of the bottle, as by the removal of the bottom thereof and re-welding of it would be of no value, since it is not possible to re-empty the bottle after it has once been emptied through the aforesaid closure. Therefore, the present invention involves not merely a non-refillable receptacle in the sense in which that term is generally used, but also involves the capacity to prevent or resist re-emptying of a bottle refilled in some way through the body thereof. By this means, the

public is assured of the genuineness of the original contents of the bottle.

The matter of construction provides for the possibility of some variation, but in order to insure the best results, it is desirable, wherever there is not an actual glass weld between two contacting glass portions, to provide for securing these parts together by a fusible cement between the separate parts which may be then fused together after being properly located in position.

It will, of course, be understood that reference herein and in the appended claims to the capacity of the present invention to preclude re-emptying of a container, refers to the fact that the container cannot be re-emptied a second time through the natural or prepared orifice for emptying the contents, without some defect or alteration occurring and becoming apparent to show that the container has been refilled.

While I have in the above description disclosed what I believe to be preferred and practical embodiments of the invention, it will be understood to those skilled in the art that the details of construction are merely by way of example and not to be construed as limiting the scope of the invention as defined in the appended claims.

What I claim is:

1. A container for liquids provided with a tubular neck, a stopper fixed in the outer end of said neck and provided with a discharge aperture and an axial bore, a stem rotatable in said bore, an axially bored cylindrical block fixed in said neck and provided at its opposite ends with aligned apertures, said stem extending through the bore of said block and having fixed thereto a pair of apertured disks cooperating with the apertured ends of said block to control the discharge of liquid from the container into said block and from the block toward said discharge aperture alternately, and means to limit the rotation of said stem to rotation in one direction only.

2. The combination set forth in claim 1, with means for preventing rotation of said stem in said direction after a predetermined number of rotations thereof.

3. A container for liquids provided with a tubular neck, a stopper fixed in the outer end of said neck and provided with a discharge aperture and an axial bore, a stem rotatable in said bore, an axially bored cylindrical block fixed in said neck and provided at its opposite ends with aligned apertures and forming between said ends a measuring chamber, said stem extending through the bore of said block and having fixed thereto a pair of disks provided with staggered apertures cooperating with the apertures in the ends of said block to control the discharge of liquid alternately from the container into said chamber and from said chamber toward the discharge aperture in said stopper, cooperating ratchet teeth formed on one of said ends and the upper disk to prevent rotation of said stem in one direction, means interposed between said stopper and said disk to hold the disk with its ratchet teeth in contact with the teeth on said end, and means to limit the number of rotations

of said stem in its permitted direction of rotation.

4. The structure set forth in claim 3, in which the last named means comprises an externally screwthreaded extension of said stem, a cage fixed to the lower end of said block, and a nut on said screw-threaded extension provided with means cooperating with said cage to limit the movements of the nut to axial sliding movement within said cage.

5. A container for liquids provided with a tubular neck, a stopper fixed in the outer end of said neck and provided with a discharge aperture and an axial bore, a stem rotatable in said bore, an axially bored cylindrical block fixed in said neck and provided at its opposite ends with aligned apertures and forming between said ends a measuring chamber, said stem extending through the bore of said block and having fixed thereto a pair of disks provided with staggered apertures cooperating with the apertures in the ends of said block to control the discharge of liquid alternately from the container into said chamber and from said chamber toward the discharge aperture in said stopper, an annular row of ratchet teeth formed on the upper face of the upper disk, a leaf spring pawl fixed to the lower face of said stopper and contacting with the teeth of said row to prevent rotation of the stem in one direction, and means on the lower end of said stem to limit the number of rotations of said stem in its permitted direction of rotation.

6. The structure set forth in claim 5, in which the last named means comprises a screw-threaded extension of the stem, a cage fixed to the lower end of said block, and a nut threaded on said extension and provided with means engaging said cage to limit the movements of the nut to axial sliding movement along said extension.

7. A container for liquids provided with a tubular neck, a stopper fixed against axial movement in the outer end of said neck and provided with a discharge aperture and an axial bore, a stem rotatable in said bore, an axially bored cylindrical block fixed in said neck and provided at its opposite ends with aligned apertures and forming between said ends a measuring chamber, said stem extending through the bore of said block and having fixed thereto a pair of disks provided with staggered apertures cooperating with the apertures in the end of said block to control the discharge of liquid alternately from the container into said chamber and from said chamber toward the discharge aperture in said stopper, said stem being extensible and provided at its lower end with external screwthreads, cooperating ratchet means between the upper end of said block and the upper apertured disk to prevent rotation of said stem in one direction, a cage secured to and depending from the lower end of said block and having a cross bar provided with a step bearing for the lower end of said stem, and a nut on said external screwthreads and engaging said cage to slide lengthwise thereof and to limit the number of rotations of said stem in its permitted direction of rotation.

LESTER L. LEWIS.
